UNITED STATES PATENT OFFICE.

EDWARD McCUALEY, OF MINNEAPOLIS, MINNESOTA, ASSIGNOR OF ONE-HALF TO
WILLIAM TERANCE McCUALEY, OF FALLOWFIELD, CANADA.

POLE-TIP.

1,082,090.

Specification of Letters Patent. Patented Dec. 23, 1913.

Application filed September 9, 1910, Serial No. 581,324. Renewed October 2, 1913. Serial No. 793,063.

To all whom it may concern:

Be it known that I, EDWARD McCUALEY, a citizen of the United States, residing at Minneapolis, in the county of Hennepin and 5 State of Minnesota, have invented a new and useful Pole-Tip; and I do hereby declare the following to be a full, clear, and exact description of my invention.

This invention relates to improvements in 10 pole tips; and the object of same is to provide a construction whereby the accidental displacement of the neck-yoke from the pole tip is prevented.

Another object is to provide a pole tip 15 which will perform the function of a runner and prevent the tongue from plowing into the ground in the event of the breaking of that part of the harness supporting the neck yoke and tongue.

I attain these objects by the construction 20 illustrated in the accompanying drawing, in which:—

Figure 1 is a side view of a pole with my improved tip. Fig. 2 is a bottom view of 25 same. Fig. 3 is a sectional view on line $x-x'$ Fig. 1. Fig. 4 is a sectional view on line $y-y'$ Fig. 1. Fig. 5 is a sectional view on line $x'-x'$ Fig. 1. Fig. 6 shows my tip as it appears in use.

The pole tip is cast in one integral piece, as 30 shown in the drawings, having a socket portion A of any desirable depth for the reception of the end of the pole 1. The top of the socket portion is provided with an extension 35 B forming a strap adapted to lie upon the upper side of the pole. On the bottom of the socket portion there is also a similar extension forming a strap C adapted to fit upon the under side of the pole. These 40 straps are provided with holes for securing them to the pole by bolts or rivets in the usual manner.

Projecting from the under side of the forward end of the socket A there is hook E 45 bent downwardly and rearwardly and whose rear end, terminating into a ball, is again bent upwardly toward the pole for the purpose hereinafter set forth. On the under side of the socket there is a lug D, adapted 50 to prevent the ring of the neck yoke from sliding back upon the pole. The hook E and the lug D are spaced apart sufficiently

to allow the yoke ring to be inserted in position upon the tip. As shown in the drawing the hook extends a considerable distance to 55 the rear of the lug D toward the heel of the pole.

By having the hook bent in the form above described should any part of the harness supporting the neck yoke become 60 accidentally broken and the pole drop to the ground the said hook will perform the function of a runner allowing it to slide upon the ground instead of plowing therein and being broken as it often happens with the 65 usual form of pole tips in use before my invention.

By my invention I have produced a pole tip neat in appearance, easy to manufacture, cast in one piece, and produced at very 70 much less cost than the usual pole tip of the form heretofore in use.

Although I have shown the socket portion of my pole tip provided with extensions forming top and bottom straps for securing 75 it to the pole it will be readily understood that these straps could be dispensed with and the socket could be made completely of a tubular form surrounding that length of the pole embraced by the straps without departing from the spirit and scope of my invention.

Having fully described my invention what I claim and desire to secure by Letters Patent is:—

A pole tip formed in one integral piece comprising a socket portion having a closed partially rounded forward end, provided with a hook forming a continuation of the curve of the rounded portion and extending downwardly and rearwardly therefrom, said hook terminating in a free end which is bent upwardly toward the rear end of the socket, a lug on the underside of the socket portion over-hanging the hook at a point 95 intermediate the length of said hook, the underside of the socket portion lying between the said lug and the hook being in a substantially straight line as shown and described.

EDWARD McCUALEY.
